US00D782511S

(12) **United States Design Patent** (10) **Patent No.:** **US D782,511 S**
(45) **Date of Patent:** **** Mar. 28, 2017**

(54) **DISPLAY SCREEN WITH GRAPHICAL USER INTERFACE**

(71) Applicant: **Espec Corp.**, Osaka-shi, Osaka (JP)

(72) Inventors: **Osamu Matsuguma**, Osaka (JP);
Yasushi Watanabe, Osaka (JP)

(73) Assignee: **ESPEC CORP.**, Osaka-Shi (JP)

(**) Term: **15 Years**

(21) Appl. No.: **29/526,722**

(22) Filed: **May 13, 2015**

(30) **Foreign Application Priority Data**

Nov. 14, 2014 (JP) 2014-025406

(51) **LOC (10) Cl.** **14-04**

(52) **U.S. Cl.**

USPC **D14/486**

(58) **Field of Classification Search**

USPC **D14/485-487**

(57) **CLAIM**

The ornamental design for a display screen with graphical user interface, as shown and described.

DESCRIPTION

The FIGURE is a front view of a display screen with graphical user interface.

The outermost broken lines in the FIGURE show a display screen and form no part of the claimed design. The remaining broken lines in the FIGURE represent portions of the graphical user interface and form no part of the claimed design.
